STORM LANTERN WITH PROTECTING RING BETWEEN GLASS AND HOOD

Filed Jan. 26, 1924

FIG.1.

FIG.2.

FIG.3.

Inventor:
Max Hanel
By John H. Smith
Attest

UNITED STATES PATENT OFFICE.

MAX HÄNEL, OF SCHLETTAU, GERMANY.

STORM LANTERN WITH PROTECTING RING BETWEEN GLASS AND HOOD.

Application filed January 26, 1924. Serial No. 688,813.

To all whom it may concern:

Be it known that I, MAX HÄNEL, a citizen of the German Republic, residing at Schleattau, Germany, have invented certain new and useful Improvements in Storm Lanterns with Protecting Rings between Glasses and Hoods, for which I have filed an application for patent in Germany on the 22nd September, 1923, and of which the following is a specification.

In order to protect the flame in the lantern against the wind a separate ring is arranged above the pane on the lower side of the hood. This protecting ring must however be very narrow as sufficient space must be left for the insertion of the glass from the side. The broader the protecting ring can be made the better it will protect the flame against the wind. The present invention has for its object to make the protecting ring rather broad and with this object in view the ring is divided into two parts, the lower part being movable and connected with the wire ring which holds the glass globe. When the wire ring is raised to insert the glass globe the lower part of the protecting ring is raised also.

The invention will be best understood from a consideration of the following detailed description taken in connection with the accompanying drawings forming a part of this specification, with the understanding that while on the drawings one embodiment of the invention is disclosed, the invention is not confined to any strict conformity with the showing of the drawings, but may be embodied in any manner which does not make a material departure from the salient features of the invention.

In the drawing only the part of a storm lantern is shown which is important for this invention.

Fig. 1 shows this part of the lantern in side elevation, the glass globe inserted.

Fig. 2 illustrates how the lower part of the protecting ring is moved in upward di-

rection together with the wire ring which serves as mounting for the glass, the glass frame being removed.

Fig. 3 is a plan view of the protecting ring in cross section.

The protecting ring consists of an upper part 2 fixed on the hood 1 of the lantern and of a lower movable part 4 attached to the upper part 2 by means of hinges 3. 55 The commonly used wire ring 5 which serves as mounting for the upper edge of the glass is connected with the lower part 4 of the protecting ring by rolled up tongues 6 or in any other convenient manner. If the wire ring 5 is pulled up with the aid of the handle 7, as shown in Fig. 2, the lower part 4 of the protecting ring is raised also so that sufficient space is made free for the insertion or removal of the glass globe 8. 65 When the glass globe is inserted and accurately mounted in the wire ring 5 the lower part 4 of the protecting ring together with the upper part 2 of the same close the joint between the glass and the hood so perfectly 70 that the flame in the lantern burns steadily even in the heaviest storm.

I claim:—

A storm lantern comprising in combination a hood, a glass globe, a movable wire ring serving as mounting for the glass globe and a protecting ring between said hood and said wire ring designed to tightly pack the joint between the glass globe and the wire ring, said protecting ring consisting of 75 an upper part rigidly fixed on the hood and of a lower movable part hingedly connected with said upper part and connected with said wire ring so that it may be pulled up with the same when the glass has to be inserted or removed.

In testimony whereof I affix my signature in presence of two witnesses.

MAX HÄNEL.
